UNITED STATES PATENT OFFICE.

IRVING L. TENNEY, OF NEW YORK, N. Y.

FOLDING HANGER.

SPECIFICATION forming part of Letters Patent No. 669,561, dated March 12, 1901.

Application filed June 11, 1900. Serial No. 19,865. (No model.)

To all whom it may concern:

Be it known that I, IRVING L. TENNEY, a citizen of the United States, residing in the city, county, and State of New York, have invented a certain new and useful Improvement 5 in Folding Hangers, of which the following is a specification.

My invention has relation to improved means whereby ladies' skirts or other garments 10 may be quickly and neatly folded for convenience in hanging or in otherwise packing in closets or trunks and whereby the required folds may be securely preserved.

By the use of my improvement a long garment 15 may be suspended within a relatively low storage-space without wrinkling or crumpling the fabric.

My improved folding hanger furthermore insures uniform action, so that a given garment 20 may always be folded in the same place. A further advantage attained is the storing or packing of a given long garment in a minimum space vertically and horizontally, while permitting quick and ready access thereto 25 without disturbing other garments stored or packed therewith.

A preferred form of my invention is illustrated in the accompanying drawings, wherein—

30 Figure 1 shows a dress-skirt hung upon one of my improved hangers in use on the side bars of a wardrobe-trunk, such as that patented to S. W. Bonsall May 17, 1898, No. 604,346; and Fig. 2 is a view of my improved hanger as 35 adapted to be hung or packed in the same location in side view.

My improved folding hanger consists, essentially, of what may be termed a "fold-bar" 1, intended to lie within the fold of the 40 garment 2, upon which fold-bar an attachment-bar 3 is secured by means of arms 4. In the form shown these arms consist of wires whose ends are looped, as at 5, around the fold-bar 1, being countersunk, as shown, to 45 prevent said loops from sliding off of the bar. It is obvious that a variety of pivotal attachments for the arms 4 equivalent to said loops may be employed without departing from the spirit of my invention, and it is to be further understood that my invention covers as

well a rigid as a pivotal connection between the fold-bar and the arms 4. The attachment-bar 3 is provided with attaching means adapted to the kind of garment intended to be folded and stored. Where a dress-skirt 2 55 is to be hung, I have found it convenient to employ hooks 6, placed at proper intervals for accommodation of the usual tapes at the skirt-belt.

The parts so far named are sufficient for 60 accomplishing the principal objects of my invention, and the device so constructed is used as follows: The top of the garment 2 is secured to the attachment-bar 3—as, for instance, by the hooks 6. The fold-bar 1 being 65 then held in a fixed position in space in one hand, the attachment-bar is swung around, as indicated by the arrow in Fig. 1. This first raises the garment above the fold-bar, bringing the latter against the garment. Then 70 as the rotation continues and the attachment-bar is depressed to complete the circle the garment bends forming a fold enveloping the bar 1, and shortening the vertical suspension by an amount equal to the length of the 75 arms 4.

It is obvious that hangers having various lengths of arms may be used according to the length of garment to be folded. Thus folded the garment may be hung or laid in a closet, 80 trunk, or bureau-drawer, as desired.

Where my improved hanger is to be used for hanging in a closet, the outer tips of the fold-bar can be utilized as points of suspension, either with or without attached hooks. 85

In the preferred form shown hooks 7 are fixed to the bar 1, which hooks are adapted to slide upon the rods 8 in a manner fully explained regarding other forms of hanger in the aforesaid patent to S. W. Bonsall. Thus 90 employed the folding of the garment may be accomplished either before or after the hanger is in place in the trunk.

Where hooks 6 are used on the bar 3, as shown, these hooks are available for hanging 95 dress-waists or other short garments after the skirt is in place.

A variety of modifications may be made in my device without departing from the scope of my invention as hereinafter claimed, and 100

I am not to be understood as limiting myself to the precise details herein shown and described.

What I claim is—

5 1. An article of manufacture consisting of an attachment-bar, means thereon for attaching a garment thereto, a fold-bar, arms joining said two bars and pivoted to said fold-bar, the two bars being arranged so that they

10 can be revolved one about the other without obstruction.

2. An article of manufacture consisting of an attachment-bar, means thereon for attaching a garment thereto, a fold-bar, and arms

joining said bars, the whole being so arranged 15 that said bars can be revolved one about the other without obstruction.

3. An article of manufacture consisting of an attachment-bar, means thereon for attaching a garment thereto, a fold-bar longer than 20 said attachment-bar, arms joining said two bars, and hanging means on said fold-bar outside of the junction with said bar of said arms.

IRVING L. TENNEY.
